Attorney

UNITED STATES PATENT OFFICE.

JOSEPH P. SHEVLIN, OF DENVER, COLORADO.

AIR PUMP.

Application filed July 10, 1922. Serial No. 574,051.

To all whom it may concern:

Be it known that I, JOSEPH P. SHEVLIN, a citizen of the United States, residing at the city and county of Denver and State of Colorado, have invented certain new and useful Improvements in Air Pumps; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

This invention relates to pumps, and has special reference to improvements in the construction of portable air pumps of the types used for inflating tires.

Air pumps are old and well known and one is carried by practically every automobile. All the pumps with which I am acquainted are provided with leather cups which serve as valves and pistons. The air usually enters the cylinder of the pump between the cylinder wall and the leather cup. This is made possible by the fact that the leather cups are, as their names imply, cup-shaped, and offer little or no resistance to the passage of air in one direction, but act as almost positive stops to the movement of air in the other direction. The passage of the air between the cup-shaped valves and the sides of the cylinder tends to dry the leather and make it brittle. A great deal of the trouble experienced with air pumps is due to the drying out and the cracking of the leather caused by the passage of the air as pointed out above.

It is the object of this invention to overcome the objection referred to above, and for this purpose I modify the construction of the valves in such a manner that the air will not have to enter the piston chamber by passing between the cylinder walls and the piston, but through openings provided therefor.

In order to more clearly describe my invention, I shall have reference to the accompanying drawing, in which

Fig. 1 is an elevation of my pump with parts thereof broken away to show the relative positions of the various parts;

Fig. 2 is a vertical section of my pump taken on line 2—2, Fig. 1;

Fig. 3 is a plan view of one of the valve members;

Fig. 4 is a side elevation thereof;

Fig. 5 is a plan view of another valve member; and

Fig. 6 is a side elevation of the member 60 shown in Fig. 5.

The same reference numerals will be used to indicate the same parts throughout the several views.

My pump consists of a base 1 having a central hollow boss 2 extending upwardly from one side thereof. The inside of boss 2 is threaded and the sides thereof are provided with an opening 3 for the reception of a hose coupling 4. A tube 5 of brass or any other suitable material has its lower end threaded to boss 2 in the manner indicated in Fig. 2; this pipe forms the high pressure cylinder of the pump. Secured to the upper end of tube 5 is a cap 6, which is shown in plan and side elevation in Figs. 5 and 6. Cap 6 has a threaded flange 7 which engages cooperating threads on the end of tube 5. A threaded stud 8 projects upwardly from the center of cap 6. Lugs 9 extend radially from stud 8 and are spaced angularly about 90 degrees apart. Shoulders 10 are formed a short distance above the upper surface of cap 6 and serve as supports for the valve 11 which will be described more in detail hereinafter. The vertical sides 12 form guides for valve 11. A leather washer 13 is placed on the stud 8 and clamped against the upper shoulders 14 by means of a nut 15. Holes 16 extend through the cap 6 and constitute the passages through which the air passes from the low pressure cylinder to the high pressure cylinder when the pump is operated in the manner to be hereinafter described.

Valve 11 consists of a leather cup 17 clamped between the sides of the ring 18 which may be formed in any suitable manner, but which is preferably pressed out of a single piece of metal of the cross section substantially like that shown. The length of the guiding shoulders 12 is greater than the thickness of valve 11, with the result that the latter is free to slide thereon and may occupy the position shown in full lines 100 in Fig. 2, or the position shown dotted in the same figure. Cap 6 has an axial hole 19 through which rod 20 slides with a close fit. Secured to the lower end of rod 20 is the high pressure piston and valve which comprises a valve member 21 having a leather cup 22 secured thereto in the same manner

as explained in connection with valve 11. Valve member 21 is held from upward movement by means of a nut 23 threadedly connected with the lower end of rod 20, and 5 from downward movement by means of a nut 24 which has a central fluted stem 25, at the lower end of which there is an annular flange 26 provided with a plurality of spaced holes 27. The valve 21 is held in 10 place on stem 25 by means of the flange 26 and nut 23. A leather washer 28 separates the valve 21 from the nut 23 and serves to form a seal when the valve 21 operates to compress the air. To the lower end of tube 15 29 I secure a cap 30 which has a central opening of a diameter equal to that of pipe 5. A downwardly extending cylindrical flange 31 is internally screw-threaded for the reception of a gland 32 which serves to 20 compress the packing material 33 by means of which an airtight sliding connection is made with tube 5. To the top of tube 29 I secure a cap 34 which has centrally thereof an upwardly projecting threaded boss 35 25 which engages corresponding threads on rod 20. Cap 34 is also provided with a number of openings 36. The upper threaded end of rod 20 extends upwardly through a handle 37 which is held in place thereon by 30 means of a nut 38.

The operation of the pump is as follows: The pump is connected to the valve stem of the tire in the usual way. The operator then holds the base 1 down by means of his 35 feet and grasping the handle 37 he raises the latter. As tube 5 is threadedly connected to the base 1 and pipe 29 is secured to the handle 37, it is evident that by raising the handle relative movement will take 40 place between tubes 29 and 5 and cause the latter to slide in the stuffing box. The movement of the handle 37 in an upward direction will, of course, cause the rod 20 to move upwardly with respect to tube 5 45 and carry with it the valve which is secured to the lower end thereof. The upward movement of tube 29 will decrease the volume of the annular space between valve 11 and cup 30, and the air contained therein 50 will flow between valve 11 and cap 6 through holes 16 into the interior of tube

5, and thence through holes 27 in member 25 to the lower side of the high pressure valve. It will be noted that during the upward stroke valve 11 will be forced upwardly against the leather washer 13 and form a seal that will prevent the air from flowing out instead of into tube 5. On the downward stroke valve 21 will be forced up against the leather washer 28 and form a 60 seal, which will prevent the air from leaking by as it is being compressed. During the downward stroke air will pass into the annular space below valve 11 through the channels provided therefor in member 6. 65

It will be noted that I have provided passages which permit the air to enter the cylinders without passing between the cylinder walls and the leather cups, as is customary in this type of pump. By means of 70 these air passages, the drying effect of the air on the leather cups is overcome to a great extent, and the valves last longer. The leather cups are secured to holders 18 and 21 and can be very easily and quickly 75 replaced by new ones whenever desired.

My pump, as above described, is of substantial construction, can be easily assembled, and is comparatively free from valve 80 troubles owing to the peculiar valve construction which reduces to a minimum the drying effect of the air.

Having now described my invention, what I claim as new is—

A valve adapted for use in an air pump, comprising an annular mounting ring, a leather cup valve member mounted in said ring, means cooperating with the annular mounting ring for permitting the free 85 passage of air therethrough in one direction, and for preventing the flow of air therethrough in the opposite direction, said means comprising a member having a flange on one end thereof, a boss extending through said mounting ring, shoulders on said 90 flange for preventing the ring from contacting with the flange, a sealing washer secured to the end of the boss opposite from the flange, and a nut for holding said 95 washer in place.

In testimony whereof I affix my signature.
JOSEPH P. SHEVLIN.
